UNITED STATES PATENT OFFICE.

OSBORNE H. SHEPPARD, OF CHICAGO, ILLINOIS.

HYPODERMIC SYRINGE.

1,157,429.

Specification of Letters Patent. Patented Oct. 19, 1915.

Application filed October 21, 1914. Serial No. 867,748.

To all whom it may concern:

Be it known that I, OSBORNE H. SHEPPARD, a citizen of the United States, and a resident of the city of Chicago, county of 5 Cook, and State of Illinois, have invented certain new and useful Improvements in Hypodermic Syringes, of which the following is a specification.

My invention relates to improvements in 10 hypodermic syringes, and has for its object the provision of an improved syringe of this character so constructed and arranged as to prevent the passage of sediment from the charge in the syringe into the needle thereof.

15 Other objects will appear hereinafter.

The invention consists in the combinations and arrangements of parts hereinafter described and claimed.

The invention will be best understood by 20 reference to the accompanying drawing forming a part of this specification, and in which,

25 Figure 1 is an elevation of a syringe embodying my invention, and Fig. 2, an enlarged detail section through the needle end thereof.

The preferred form of construction as 30 illustrated in the drawing comprises an ordinary hypodermic syringe barrel 3 provided with the usual piston and operating means, as will be readily understood. This syringe is equipped with a perforated needle 4 adapted to be inserted under the skin of the patient in the usual manner. Needle 4 is 35 mounted in a detachable cap 5 which is provided with internal threads 6 adapted to engage a correspondingly threaded nipple on the syringe barrel in position to receive the charge from the syringe. At its inner end 40 7, needle 4 is extended well into the opening in cap 5 and is provided with a spreading head or flange 8, as shown in Fig. 2. By this arrangement, it will be observed, that when the charge is forced out of the syringe 45 barrel 3 through the hollow needle 4 a whirlpool will be formed in the cap 5 around the inwardly projecting end 7 of needle 4, said whirlpool tending to throw any sediment in the charge outwardly against the sides of 50 the cap down which said sediment will travel into the space 9 below the inner end of needle 4 which thus constitutes a sediment well

for the collection of any sediment in the syringe charge. The outwardly spreading head or flange 8 tends to prevent the passage of this sediment outwardly through the needle, as will be readily understood. I find that this arrangement prevents the discharge of sediment into the needle and the consequent clogging and rusting thereof to 55 such an extent that it is not necessary to employ the usual cleaning wires with the needle. I have also found that this arrangement tends to prevent the inclusion of air in the charge as it enters the patient which 60 is an additional advantage from a medical point of view.

While I have illustrated and described the preferred form of construction for carrying my invention into effect, this is capable of 70 variation and modification without departing from the spirit of the invention. I, therefore, do not wish to be limited to the precise details of construction set forth, but desire to avail myself of such variations and 75 modifications as come within the scope of the appended claims.

Having described my invention what I 80 claim as new and desire to secure by Letters Patent is:

1. The combination with a hypodermic syringe, of a needle projecting well into the discharge end thereof and provided at its extreme inner end with a flange forming a spreading head situated centrally in the 85 syringe with free space surrounding it so as to insure free circulation under said head, substantially as described.

2. The combination with a hypodermic syringe, of a cap threaded thereon and constituting the discharge end of the syringe; and a needle projecting well into said cap and provided at its extreme inner end with a flange forming a spreading head situated 90 centrally in the syringe with free space surrounding it so as to insure free circulation under said head, substantially as described.

95 In testimony whereof I have signed my name to this specification in the presence of two subscribing witnesses.

OSBORNE H. SHEPPARD.
